UNITED STATES PATENT OFFICE.

JOSEPH KONCINSKY, OF NORWICH, CONNECTICUT.

SPINNING TOY.

Application filed March 7, 1925. Serial No. 13,772.

To all whom it may concern:

Be it known that I, JOSEPH KONCINSKY, a citizen of the United States, residing at Norwich, in the county of New London and 5 State of Connecticut, have invented certain new and useful Improvements in a Spinning Toy, of which the following is a specification.

This invention relates to an improved 10 spinning toy, sometimes referred to as a whirligig.

The invention has more particular reference to a spinning toy of this class which embodies a stem provided with a bladed fan 15 for producing what may be generally termed a rotor adapted to ascend into the air under the rapid rotation imparted thereto.

The principal feature of the invention is 20 the particular construction of the stem of the rotor which is provided intermediate its ends with an ovate enlargement of a pre-determined size serving to steady the rotor in its flying operation and to decidedly increase the momentum and inertia.

25 The feature referred to will become more apparent from the following description and drawing:

In the drawing

Figure 1 is a top plan view of a toy constructed in accordance with the present invention, and

Fig. 2 is a side elevation thereof.

Referring to the drawings in detail, the reference character 1 designates generally a 35 bladed fan constituting a part of the so-called flying rotor. As is better shown in Fig. 2, the blades 2 are disposed obliquely to the line of ascension to facilitate upward travel.

40 The stem which is fastened in any appropriate manner to the center of the fan embodies an upper downwardly tapered portion 3, a lower tapered portion 4, of a greater length, and an intervening substantially ovate enlargement 5 acting somewhat in the capacity of a weight.

For the purpose of supporting the rotor before it is set into rotation, I provide an appropriately shaped handle 6 provided at its 50 outer end with a ring-like head 7 through which the lower tapered portion of the stem extends and in which said portion is rotatable. This head 7 is provided on one side with a guide eye 8 through which the 55 free end portion of the cord 9 passes.

The lower tapered end of the portion 4 is provided with a longitudinal groove in which the opposite free end portion 11 of the cord is received. In practice the last named end 11 of the cord 9 is placed in the 60 groove provided and the cord is wrapped around the tapered portion 4 of the stem and the opposite upper end 9 is brought through the eye 8. The device is now ready to be spun. The handle 6 is grasped and 65 the end 9 of the cord is pulled to set the rotor into rotation under the action of the unwinding of the wrapped cord.

With the parts in the position shown in Fig. 2, the enlargement 5 serves somewhat 70 in a manner to balance the device when it is in the operator's hand and serves therefore as a shoulder to rest upon the head 7 to relieve the cord of undue stress.

As the device ascends into the air, it is 75 carefully righted under the action of the weighted enlargement 5 and in practice it has been shown that it will travel approximately one hundred and fifty feet or more in the air, the line of ascension being substantially directly upwardly and overhead under most conditions, due to the increased inertia caused by the existence of the weighted enlargement on the stem.

Consequently, when the device falls, the 80 weight will also serve to increase a comparatively straight descension so that in the use of the device, it will not be carried an unreasonable distance from the operator's standing place, except in strong winds. 85

Although I have shown and described the preferred embodiment of the invention, it is to be understood that minor changes coming within the field of invention claimed 90 may be resorted to if desired.

Having thus described my invention, what I claim as new is:—

In a whirligig of the class described, a rotor adapted to ascend into the air, said rotor comprising a bladed fan provided with a depending stem, said stem having upper and lower tapered portions joined together by a substantially ovate enlargement serving as a weight to steady and right the rotor in its flight. 100

In testimony whereof I affix my signature,

JOSEPH KONCINSKY.
